UNITED STATES PATENT OFFICE.

RUDOLPH C. SMITH, OF YONKERS, NEW YORK, ASSIGNOR OF ONE-HALF TO
JAMES CRUICKSHANK, OF KINGSTON, NEW YORK.

ELEVATOR.

SPECIFICATION forming part of Letters Patent No. 601,909, dated April 5, 1898.

Application filed October 19, 1897. Serial No. 655,722. (No model.)

To all whom it may concern:

Be it known that I, RUDOLPH C. SMITH, a citizen of the United States of America, and a resident of Yonkers, Westchester county, New York, have invented a new and useful Improvement in Elevators, of which the following is a specification.

The invention relates to improvements in elevators; and it consists in a novel safety appliance to mitigate or avoid the consequences resulting from a fall or runaway of an elevator-car.

I present the invention in this application as embodied, for illustration, in an elevator comprising the usual car and shaft, the latter being provided with suspended slideways having a safety stop-clamp thereon and the car being provided with a projection or dog normally in the vertical plane of said stop, but capable of being removed therefrom at a definite point in the line of travel of the car in order that the dog may, when desired, pass said stop without touching the same. The shaft is provided with a bar-rail adapted to retain the dog in the vertical plane of said stop and at a definite point in the line of the travel of the car to permit the attendant to withdraw the end of the dog from the vertical plane of said stop in order that said dog may pass free of the stop. The slideways upon which the stop-clamps are placed are preferably of wood and have an increased diameter below the normal position of the stops, and these stops are preferably in the form of closed clamps encompassing transversely the slideways and do not move on the latter except when the weight of the car is brought upon them, at which time the said stop-clamps will by the weight of the car and its contents be driven downward on the slideways and will scrape and cut into the latter, so as to arrest the car by a constant retarding resistance, which will produce a uniformly decreasing motion in the car until the latter comes to a standstill.

The invention will be more fully understood by reference to the accompanying drawings, in which—

Figure 1 is a vertical section of an elevator-shaft, showing the car connected to a hoist-

ing-gear, the car and shaft being provided with means constructed in accordance with and embodying the invention. The shaft in this figure is broken horizontally, and the figure illustrates the lower part of the shaft, 55 possessing the slideways, and the upper part of the shaft, at which the usual sheaves are placed for the hoisting rope or cable. Fig. 2 is a horizontal section through the car, shaft, and connected parts looking downward upon 60 the safety appliances constituting my invention; and Fig. 3 is an enlarged side elevation of one of the dogs, shown in its relation to the stop-clamps and slideways. This figure also shows an enlarged top view of a portion of 65 one of the clamps or stops.

In the drawings the numeral 1 indicates a car, and 2 the customary guide-rails secured to the guide-posts 3.

The car 1 is suspended by means of a suitable hoisting rope or cable 4, which passes over the sheaves 5 to any suitable hoisting apparatus 6. The car will be provided with any of the usual forms of control—hand-rope, lever, or electrical connections—for stopping, 70 starting, and controlling the same.

The car is provided with a hand-lever 7, which has its fulcrum at 8 in a stand 9, secured to the bottom of the car, and the lower end of the lever 7 passes through the bottom 80 of the car with sufficient clearance for operation. Underneath the floor of the car is pivotally mounted a three-armed lever, the arm 12 of which is by means of the rod 10 connected with the lower end of the lever 7, 85 while the arms 13 13 of said three-armed lever are by means of links connected with the dogs 14 14, which are adapted to slide in the inclosing casings 15 15 under the action of said three-armed lever. The casings 15 are 90 secured to the bottom of the car and support the dogs 14. The movement in one direction of the three-armed lever will set the dogs 14 in their normal running position, which is that illustrated in Fig. 3, and the movement 95 of said three-armed lever in the opposite direction will withdraw the dogs 14 inward, so that they will pass clear of the safety stops or clamps hereinafter referred to. The dogs 14 and the three-armed lever with which they 100

are connected may be directly operated by the attendant in the car through the medium of the lever 7.

Extending lengthwise of the elevator-shaft 5 is the bar or rail 20, and the upper end of the lever 7 carries a pin or shaft 18, upon which is placed a roller 19 for engagement with said bar or rail 20 during all of the travel of the car above the point at which the safety-stop 10 appliances are intended to operate, and suitably adjacent to this point the bar or rail 20 is provided with the outward curve 21 for the purpose of permitting the outward movement of said lever 7 and the consequent inward 15 movement of the dogs 14, whereby the said dogs may be permitted to escape contact with the stops or clamps to be hereinafter referred to. The dogs 14, as above described, are normally in their outward position (shown in 20 Fig. 3) and always remain in this position, except when the upper end of the lever 7 is moved into the outward curve 21 of the bar or rail 20. The straight portion of the bar or rail 20, by its contact with the upper end of 25 the lever 7, imperatively maintains the dogs 14 in their outward position, and the attendant in the elevator, upon arriving at the outward curve 21 of said bar or rail, must move the upper end of the lever 7 outward into 30 said curve 21 if he would prevent the dogs 14 from engaging the stop-clamps and arresting the car. The dogs 14 have their outer ends hook-shaped to securely engage the stop-clamps when meeting the latter upon the 35 scent of the car, and the outer surfaces of the ends of the dogs 14 are tapered downward and outward on a slanting line, so that said ends may not pass into operative engagement with the stop-clamps during the ascent of 40 the car.

The slideways are preferably of wood and are indicated by the numeral 17, in the present instance two slideways being provided at one side of the elevator-shaft and two slide- 45 ways at the other side of said shaft. The slideways 17 are secured at their upper part to the side of the elevator-shaft, and hence said slideways are in a suspended condition and have their lower portions free to afford 50 a retarding slide to the stop-clamps 16, which are applied upon the upper portion of said slideways. The stop-clamps 16 encompass the upper portions of the slideways 17, where said slideways are of slightly less cross-sec- 55 tion than below said stop-clamps, whereby a shoulder 30 on the slideways is formed and maintains the stop-clamps in a normally stationary position. In the present instance I have formed each of the stop-clamps 16 to 60 engage two of the slideways 17, and, as indicated in the drawings, the dogs 14 protrude outward on a vertical line extending between the slideways 17 in position to engage the central portions of the stop-clamps 16. The 65 inner surfaces of the stop-clamps 16 are preferably serrated, as indicated in Fig. 3, in or-

der that they may engage and cut into the slideways 17 in case of accident.

The accompanying drawings illustrate the slideways 17 as suspended near the lower portion of the elevator-shaft, and it is my purpose to employ slideways 17, which shall be about one-fifth of the entire height of the elevator-shaft, in order that the stop-clamps may be normally located at about one-fifth 75 of the rise of the car, since this arrangement and construction will give a safety sliding distance for a gradual stop in case of an emergency.

During the ordinary travel of the car the 80 safety-dogs 14 are in their outward or extended position (shown in Fig. 3) in order that in case of an accident resulting in the fall of the car the outer ends of said dogs may be in position to engage said stop-clamps 16. When 85 during the usual employment of the car the latter is approaching the outward curve 21 of the car or rail 20, it will be the duty of the attendant to push the upper end of the lever 7 outward into said curve in order that the dogs 90 14 may be withdrawn inward and pass free of the stop-clamps 16. The outward curve 21 is of such predetermined length that there will not be time enough for the upper end of the lever 7 to enter the same whenever the 95 speed of the car exceeds a fixed limit, and thus in case of a fall of the car the upper end of the lever 7 will not enter the outward curve 21 of the rail 20, and the dogs 14 will, as a consequence, remain in their outward position and engage the stop-clamps 16. In the event of an accident and the fall of the car the dogs 14 will engage the stop-clamps 16 and drive the latter downward upon the slide- 100 ways 17, the serrations of the stop-clamps 105 abrading or cutting into the slideways, whereby the car will be stopped with a uniform and even resistance and not suddenly. The slideways 17 are preferably of wood, since this material offers a uniform resistance; but 110 they may be of other material and of any desired shape. When the weight of the car is brought upon the stop-clamps, the latter move downward upon the slideways 17 and thereby a uniformly decreasing motion of the 115 elevator-car until the latter comes to a standstill is secured.

The form of the shoulder 30 on the slide- 120 way 17 is not of material consequence, since whatever be the form of the slideway 17 the object is that the stop-clamps shall by their abrading downward action and motion create a constant resistance. In all cases the slide-ways 17 should be so proportioned that their surplus material to be abraded by the stop- 125 clamps shall enable the production of the constant retarding resistance which will secure the uniformly-decreasing motion of the elevator-car until the latter comes to a stand- still.

The present invention is intended only as an emergency-brake and may only come into 130

play a few times during the entire life of the elevator apparatus.

The operation of the elevator illustrated is the same as usual, except that the attendant when passing the curve 21 in the rail 20 will press the upper end of the lever 7 into said curve, and thereby prevent the dogs 14 from engaging the stop-clamps 16.

It is evident that the movable dogs 14 and curve 21 will be dispensed with whenever the car in its ordinary course does not pass below the stop-clamps 16, but always stop, except in case of accident, before the car could strike the stop-clamps. In this latter arrangement a permanent projecting arm or other rigid structure of the frame of the car placed to contact with the stop-clamps 16 in case of accident would take the place of the special dog 14 shown. In other words, under the conditions just cited the car would employ a fixed dog 14 to engage the stop-clamp instead of a movable dog 14, since the movable feature of the dog 14 is only useful when the car in its usual course of travel is obliged to pass by the stop-clamps 16.

A great advantage derived from suspending the slideways 17 from a point of the elevator well or shaft and leaving them free on all sides to be acted upon by the clamps, as well on the face as on the back, is that this arrangement keeps the slideways in line for direct tension and takes up the least space between the car and elevator-shaft. The slideways 17 may be easily replaced by new ones whenever in case of an accident a sufficient length of their surface has been abraded by the stop-clamps 16.

It is one of the purposes of the present invention, as above explained, to secure a constant retarding resistance which will produce a uniformly-decreasing motion of the elevator-car until the latter comes to a standstill, and I have found that an abrading cut of one inch in width and from one-eighth to one-quarter of an inch in depth in yellow-pine slideways offers a constant resistance against abrasion of about one thousand pounds. With this example of resistance given it is an easy matter to calculate the total aggregate width of the abrading cut of all of the slideways for a given height of fall.

What I claim as my invention, and desire to secure by Letters Patent, is—

1. The combination with an elevator-car having a projecting part, of an elevator-shaft in which said car moves, slideways supported in tension by said elevator-shaft, and the normally stationary clamps on said slideways to be engaged by said projecting part of the car structure, the portion of the slideways below said clamps being proportioned to resist the

motion of the clamps and the latter being slidable by abrading the slideways, as described.

2. The combination of an elevator-car having movable dogs with an elevator-shaft in which said car moves, slideways supported in tension by said elevator-shaft, clamps normally stationary on said slideways and in the path of the movable dogs but slidable by abrasion on said slideways, and means to keep the dogs from striking the stop-clamps when the car travels at a safe speed, as described. 65

3. The combination of an elevator-car having movable dogs, with an elevator-shaft in which said car moves, slideways supported in tension by said elevator-shaft, stop-clamps normally stationary on said slideways, and in the path of the movable dogs, but slidable by abrasion on said slideways, means for 75 keeping the dogs from striking said clamps when the car travels at a safe speed, and a compulsory track for maintaining said dogs in a normally outward position, as described. 80

4. The elevator-car, the movable dogs carried thereby, and mechanism for operating said dogs, combined with suspended slideways located in the elevator-shaft and arranged in pairs, and the stop-clamps encompassing said slideways and normally stationary thereon, 90 the inner surfaces of said clamps being serrated and said slideways below the normal stationary position for said clamps being of greater cross-section than at said clamps; substantially as set forth. 95

5. The elevator-car, the movable dogs carried thereby, the lever mechanism for operating said dogs, and the stationary rail for said lever mechanism, the said rail having an outward curve at a definite point, combined with the suspended slideways in the elevator-shaft, and stop-clamps on said slideways and in the path of said dogs when the latter are in their normal outward position, said slideways having a greater cross-section 100 below than at said stop-clamps; substantially as set forth. 105

6. The car having a projecting arm, combined with a vertical slideway suspended in the elevator-shaft, and a stop-clamp on said 110 slideway and normally stationary thereon and in the path of said projecting arm; substantially as set forth.

In testimony that I claim the foregoing as my invention I have signed my name, in presence of two witnesses, this 18th day of October, 1897. 115

RUDOLPH C. SMITH.
